(57) **CLAIM**

The ornamental design of a smoker with sloping top surfaces, as shown and described.

DESCRIPTION

FIG. 1 is a perspective view of a smoker with sloping top surfaces showing my new design;

FIG. 2 is a front elevational side view thereof;

FIG. 3 is a rear elevational view thereof;

FIG. 4 is a left side elevational view thereof;

FIG. 5 is a right side elevational view thereof; and,

FIG. 6 is a top plan view thereof, the bottom plan not forming any part of the invention.
